(57) **CLAIM**

The ornamental design for a bending die set, composed of a bend die post and wiper die post, for a rotary draw bending machine, as shown and described.

DESCRIPTION

FIG. 1 is a front perspective view of the bending die set, composed of a bend die post and wiper die post, for a rotary draw bending machine.

FIG. 2 is a front side view of the bending die set, composed of a bend die post and wiper die post, for a rotary draw bending machine.

FIG. 3 is a rear side view of the bending die set, composed of a bend die post and wiper die post, for a rotary draw bending machine.

FIG. 4 is a top view of the bending die set, composed of a bend die post and wiper die post, for a rotary draw bending machine.

FIG. 5 is a bottom view of the bending die set, composed of a bend die post and wiper die post, for a rotary draw bending machine.

FIG. 6 is an end view of the bending die set, composed of a bend die post and wiper die post, for a rotary draw bending machine; and,

FIG. 7 is an end view of the bending die set, composed of a bend die post and wiper die post, for a rotary draw bending machine opposite of that showing in FIG. 6.

1 Claim, 5 Drawing Sheets
